(57) **CLAIM**

The ornamental design for a cyliner for an air compressor, as shown and described.

DESCRIPTION

FIG. 1 is a perspective view of a cyliner for an air compressor showing my new design;

FIG. 2 is a front elevational view thereof;

FIG. 3 is a rear elevational view thereof;

FIG. 4 is a right side perspective view thereof;

FIG. 5 is a left side perspective view thereof;

FIG. 6 is a top plan view thereof;

FIG. 7 is a bottom plan view thereof; and,

FIG. 8 is another perspective view thereof, with the air compressor engaged.

The dotted line showing of the air compresor is for illustrative purposes only and forms no part of the claimed design.
